UNITED STATES PATENT OFFICE.

HENRY A. LEE, OF GLEN RIDGE, ASSIGNOR TO HIMSELF, AND THEODORE W. BURGER, OF DUNELLEN, NEW JERSEY.

SHEET-METAL CAN.

SPECIFICATION forming part of Letters Patent No. 393,566, dated November 27, 1888.

Application filed July 23, 1888. Serial No. 280,738. (No model.)

To all whom it may concern:

Be it known that I, HENRY A. LEE, of Glen Ridge, in the county of Essex and State of New Jersey, have invented an Improvement 5 in Sheet-Metal Cans; and the following is declared to be a description of the same.

My invention relates to what is known in the trade as "glass-front cracker-cans" or "exhibition-cans," in which cans there is a glass 10 front and an intermediate sliding partition, which partition separates the can into two compartments, both of which compartments contain the crackers or other goods, the outer compartment showing through the glass its 15 contents to the purchaser and the inner compartment containing the goods to be sold, and in said cans as heretofore made the partition was liable to become misplaced and lost, and such cans were not constructed in an advan- 20 tageous manner for taking to pieces and cleaning.

My invention consists in a can having a removable partition, which partition is held in place by stops and a wire brace near the bottom 25 of the can and by engaging-catches at the top, and in my can the glass front is removable, and there is a frame having a gilded or colored surface, which forms a backing to the glass, and the glass is held in place by stops 30 near the bottom of the can and by strips upon the sides that are adapted to be bent over to hold the parts in place.

In the drawings, Figure 1 is a vertical section of my improved can, and Fig. 2 is a sectional plan of the same at the line $x-x$ of Fig. 1. Fig. 3 is a cross-section at the line $y-y$ in larger 35 size, and Fig. 4 is a sectional plan at the line $z-z$.

The can proper is composed of the bottom a , sides b , end c , all of sheet metal, and there 40 is a hinged lid at d and a top portion or strip, d' , to which the lid d is hinged, and e represents the glass front.

f' represents the partition, of sheet metal, the edges of which are bent over, and said partition 45 separates the can into two compartments, X Y —namely, an outer or exposed compartment, X , and an inner or concealed compartment, Y , into both of which compartments the crackers or other articles are to be 50 placed for exhibition and sale, and there is a

brace or frame, f' , made of wire, sheet metal, or other material, and hinged to the lower edge of the partition f , and this brace or frame f' is preferably of the size of the inner surface of the compartment Y , and there are stops g , 55 of tin, soldered to the bottom and sides of the can in the outer compartment, and the lower edge of the partition f bears against one end of the stops g , and is held in place on one side by said stops and on the other side by the wire 60 brace or frame f' . The top of the partition f rests against and is secured by the hinged catch h , said catch being pivoted or secured to the top d' .

i represents the metal frame which acts as a 65 backing around the glass front e , and said frame and the glass e are held in place at their lower corners by the stops g , between which and the corners of the can said glass and frame are received, and they are held in place 70 near their upper ends by the strips of metal n , that are soldered to the sides of the can, and are adapted to be bent over to hold the glass and frame in place. Said metal frame i may have an ornamental surface next the glass, 75 which surface may be gilded or colored in any desired manner, the same showing through the glass, and said frames are interchangeable, so that a frame having any desired surface can be employed in the can. 80

The hinged lid d gives access to the can-partition Y , and when the same is emptied of its contents the wire brace or frame f' can be raised and closed up against the partition f , the movement being represented by the dotted lines, Fig. 1, and the hinged catches h raised to release the partition f , so that the same can be removed from the can to give access to the contents of the front compartment, X . The glass e and frame i can be readily removed by bending back the strips n , and with the glass and frame and partition removed from the can the same can be readily cleansed after its contents are removed. 90

I claim as my invention—

1. The combination, in a can, with the removable partition, of a glass, e , a metal frame or backing, i , for the same, stops g , for holding said glass and frame at the lower corners, and metal strips n , to secure said glass and frame 100

near the upper corners, substantially as set forth.

2. The combination, in a can, with the glass front and frame, of the partition *f*, the brace 5 or frame *f'*, hinged to the lower edge of the partition, the stops *g*, secured to the can, and the hinged catches *h*, adapted to engage and secure the top of the partition, substantially as set forth.
- 10 3. The combination, in a can, of the glass *e*, the frame *i*, the removable partition *f*, and brace or frame *f'*, hinged to said partition, stops *g*, secured to the lower portion of the can and acting to confine the lower ends of 15 the glass and frame and partition, strips *n*, confining the upper portion of the glass and

frame, and hinged catches *h*, secured to the top of the can and adapted to secure the top of the removable partition, substantially as set forth.

- 20 4. The combination, with a sheet-metal cracker or exhibition can, of a removable partition and a brace or frame hinged to one edge of the same and of a size adapted to fit within the can, and a support for the partition on the 25 side opposite the brace, substantially as set forth.

Signed by me this 16th day of July, 1888.
HENRY A. LEE.
